CONVERTIBLE ICE BUNKER FOR
REFRIGERATOR CARSArthur F. O'Connor, Chicago, Ill., assignor to
Union Asbestos & Rubber Company, Chicago,
Ill., a corporation of Illinois

Application November 14, 1942, Serial No. 465,552

23 Claims. (Cl. 62—19)

The invention relates to refrigerator cars and more particularly to refrigerator cars having a transverse bulkhead forming one of the walls of an ice bunker in the end of the car; the bulkhead being movable from ice bunker forming position to a stored position adjacent the walls of the car. The purpose of moving the bulkhead to a stored position is to provide a longer lading compartment in the car when ice bunker refrigeration is not required. It is estimated that not more than twenty-five per cent of the loads hauled in refrigerator cars require ice bunker refrigeration and, inasmuch as a large majority of the existing refrigerator cars have ice bunkers permanently built in the ends thereof (bunkers which can not be folded or stored in an out-of-the-way position), the importance of the movable bulkhead will be readily understood due to the larger load which may be placed in the car.

Refrigerator cars having ice bunkers in the ends thereof are usually provided with hatch openings in the roof of the car, above the ice bunkers, as a means of loading ice into the bunkers. When bulkheads are moved to stored positions it will be understood that part of the lading will be below these hatch openings and, as certain commodities are moved under ventilation (the hatch covers being open or partly open), it will be seen that the lading beneath the open hatches requires protection from the elements, such as rain, cinders and dirt which might descend upon the lading unless means are provided to direct these elements away from the lading. The prior art shows deflectors of different kinds placed underneath the hatch openings to deflect the harmful elements from the lading; such deflectors usually being units separate from the bulkhead proper.

The most efficient ice bunker is one having vertical ice retaining walls on all four sides of the bunker, these walls being spaced from the adjacent walls of the car and bulkhead, providing vertical air ducts around the four vertical sides of the ice mass in the bunker. This type of ice bunker is known as a "basket" bunker and was recommended by the U. S. Department of Agriculture as a standard ice bunker, in its bulletin No. 1398, after exhaustive research to determine the best type of ice bunker.

Numerous types and designs of convertible bunkers and movable bulkheads have been tried out but most of them eliminated the highly desirable air duct between the car side walls and the ice mass, due to the fact that the side wall ducts interfered with moving the bulkhead from

extended position to stored position and also interfered with the highly desirable flush side walls of the lading compartment. The lading floors and side walls of the lading compartment are required by most shippers to be flush (free from any projections or recessed portions against which the lading might be damaged due to the shifting of the load longitudinally of the car) as insurance against damaged lading and in order to permit the orderly vertical stacking of the lading (such as crates and cartons), the cubical capacity of the lading compartment in many refrigerator cars being figured out so that a certain number of crates or cartons will snugly fill the lading space and eliminate loose packing of goods which might shift and become damaged in transit.

One of the objects of the present invention is to provide a movable bulkhead and a deflector, both of which combine to form the bulkhead for separating the ice bunker from the lading compartment, when in extended positions, thereby eliminating the necessity for a deflector unit in addition to the bulkhead.

Another object is to provide a convertible ice bunker having a highly desirable and efficient side wall duct in the ice bunker; the construction of the duct being such that it will not interfere with moving the bulkhead and will preserve the desirable flush lading compartment wall at all times.

A further object is the provision of a movable bulkhead of lesser dimensions and of lighter weight than the conventional bulkhead (extending substantially from the car ceiling to the car floor) thereby reducing the cost of the bulkhead and providing a bulkhead which can be easily moved from one position to another.

A further object is the provision of novel means for providing a bulkhead supporting track flush with the inner surface of the lading compartment side wall.

A further object is to provide a deflector for the hatch opening which will permit the exterior air to enter the car and which will deflect harmful elements away from the lading.

Another object is to provide novel means for moving the deflector to its raised position and the provision of novel means for locking it in its several positions.

A further object is to provide new and novel means for providing a substantially flush end wall for the lading compartment, when the bulkhead is in stored position and the provision of

novel means for locking this flush end wall in retracted position.

Another object is to provide novel means for bracing the bulkhead from the car end wall; this means being retractible and nestable with the bulkhead when not in use.

These and other objects and capabilities of the invention will be apparent from a study of the following description and the accompanying drawings.

In the drawings,

Figure 1 is a transverse vertical sectional view of a portion of a car end, taken along line 1—1 of Fig. 2, the bulkhead bracing arms being shown in retracted position.

Fig. 2 is a longitudinal vertical sectional view of the same portion of the car end, taken along line 2—2 of Fig. 1, the bulkhead bracing arms being shown in operative position.

Fig. 3 is a longitudinal vertical sectional view taken along line 3—3 of Fig. 1, showing the bulkhead and its associated parts in stored position.

Fig. 4 is a horizontal sectional view taken along line 4—4 of Fig. 2, showing the bulkhead in fixed, extended position.

Fig. 5 is an elevational view of a portion of the side wall duct and the bulkhead supporting track means, taken along line 5—5 of Fig. 4.

Fig. 6 is an elevational view of the end wall portion of the car, taken along line 6—6 of Fig. 2.

Fig. 7 is a fragmentary sectional view of the deflector, taken along line 7—7 of Fig. 1.

Fig. 8 is a fragmentary sectional view showing one method of locking the deflector catch in operative position.

Fig. 9 is a fragmentary sectional view showing the catch means of Fig. 8 secured in retracted position.

Fig. 10 is a side view of the member used to lock the deflector catch in extended and retracted positions.

In the drawings, the reference numeral 10 indicates the top wall, while 12, 14 and 16 indicate the side wall, end wall and bottom wall of the car, respectively; all of which may be of conventional insulated construction. The car ceiling 18 may have an upwardly offset portion 20 above the ice bunker, within which offset portion the deflector may be nested when in raised position in order to preserve a substantially flush ceiling line above the lengthened lading compartment. A hatch 22 may be provided in the top wall 10, above the ice bunker and an ice supporting grate 24 may define the bottom wall of the ice bunker. A floor rack 26 may be provided in the lading compartment of the car and may be separated from the grate 24 by a transversely extending plate member 28, located coincident with and below the lower margin of the extended bulkhead. The ice grate 24, the floor rack 26 and the plate member 28 may all be supported in overlying, spaced relationship with the car floor 30 whereby to provide an air duct between the ice and the car floor and between the lading and the car floor, to permit the free circulation of the chilled air throughout the length of the car floor.

A transversely extending bulkhead 32 may be provided to separate the lower portions of the ice bunker and the adjacent lading compartment and it will be noted that the vertical dimension of this bulkhead is considerably less than the like dimension of the conventional movable bulk-

head. One of the important advantages of this smaller bulkhead is its lower cost, lighter weight and the greater ease with which it may be moved. The conventional bulkhead extends substantially from the car ceiling to the lading floor and is rigidly constructed throughout its entire area in order to resist the shifting of the car lading on one side and the ice mass on the other side, due to sudden shocks received in service, as by sudden starting and stopping of the car in car switching service. Inasmuch as the lower part of the lading produces most of the shocks and stress against the bulkhead, it is obvious that the lower portion of the bulkhead must meet certain requirements of rigidity and strength, whereas the upper portion does not require the same strength. The bulkhead 32 of the present invention is intended to extend from the lading floor to a point above the lower half of the car interior. A deflector 34 may be provided above and in coplanar alignment with the bulkhead 32 to complement the bulkhead 32 in providing a wall dividing the ice bunker from the lading compartment and extending from the car ceiling to the lading floor.

The bulkhead 32

The bulkhead 32 may include a rectangular frame having opposed vertical marginal posts 36 of box-like construction and intermediate aligned posts 38 of substantially U-shaped construction having open sides facing the ice bunker. The posts 36 and 38 may be secured adjacent their upper ends to a horizontal frame member 40 and may have their lower ends secured to a horizontal frame member 42. A wooden lining 44 may be affixed to the lading compartment side of the bulkhead frame and a metallic lining 46 (either perforate or imperforate) may be affixed to the ice bunker side of the frame; lining 44 and 46 being in parallel spaced apart relationship, providing a vertical air duct therebetween. The intermediate posts 38 may be provided with opposed outwardly extending marginal flanges adapted as mounting means for the lining 46 and may have longitudinally extending bulkhead bracing arms 48 nested within the channels of the posts and pivotally connected to the posts adjacent the upper portions thereof; the arms 48 being selectively swingable upwardly to a horizontal position, with the free end portions thereof adapted to interlocking engage a keeper member 50 secured to the car end wall. The side posts 36 may be provided adjacent their upper ends with rollers 52, adapted to movably support the bulkhead upon track means 54 affixed to the side wall of the car.

The deflector 34

The deflector 34 may include a rectangular frame having aligned vertical posts 56 of box-like construction, an angular horizontal top frame member 58 secured to the upper ends of the posts 56, and an angular horizontal lower frame member 60 secured to the lower ends of the posts 56. A metallic sheet 62 may be affixed to the lading compartment side of the frame and may be provided with a series of apertures having inwardly flanged marginal portions 64, adjacent the upper margin of the sheet 62. The marginal portions 64 of the apertures may extend perpendicularly to the plane of the sheet 62 and form a continuous flange around the periphery of each aperture. A wooden lining 66 may

be affixed to the outer surface of the sheet 62, intermediate the lower margins of the apertures and the lower margin of the sheet 62. A vertically corrugated sheet 68 may be provided in parallel spaced relationship with the sheet 62, adjacent the opposed vertical sides of the deflector and may have one vertical margin affixed to a side post 56 with its opposed vertical margin extending inwardly and affixed to the sheet 62; the apices of the corrugations on one side of the sheet 68 being in coplanar alignment with the lining 46 of the bulkhead and the apices of the corrugations on the opposed side of the sheet 68 being in coplanar alignment with the edges of the marginal portions of the aperture flanges. The corrugated sheet 68 may be imperforate in the area opposite the adjacent apertures and may be perforate from a point below the apertures to the lower margin of the corrugated sheet. The inwardly extending vertical margin of the sheet 68 (affixed to the sheet 62) may be provided with vertically aligned apertures 70.

The upper margin of the corrugated sheet 68 may be affixed to the top frame member 59 (as by welding) and the lower margin may be affixed to the sheet 62, intermediate posts 56, by means of U-shaped spacing members 72; any number of the members 72 being used. A perforate metallic sheet 74, or its equivalent, may be affixed to the center post 56, with its opposed vertical margins affixed (as by welding) to the opposed corrugated sheets 68; the sheet 74 being in a common plane with the apices of the corrugations facing the ice bunker. One or more of the posts 56 may extend below the lower margin of the deflector whereby they may overlap the upper margin of the bulkhead 32 and nest within the channel portion of one or more of the bulkhead posts 38 in order to limit the movement of the deflector toward the lading compartment. The deflector 34 may be hingedly secured to the top wall 10 by means of hinges 16, whereby the deflector may be swung from vertical position to a horizontal nested position within the offset ceiling portion 20, in which latter position it will underlie the hatch 22, permitting the entrance of air and deflecting undesirable air-borne elements toward the end wall of the car where they may pass downwardly along the car end wall and into the depressed floor pan 18, and out of the car through the conventional floor pan outlet (not shown), along with the ice meltage.

The end wall lining

The conventional end wall lining comprises spaced apart vertical strips to which is affixed a metal perforate lining, the lining covering the entire area of the end wall and being spaced therefrom to form a vertical air duct between the lining (and the ice mass) and the end wall of the car. It will be seen that if the bulkhead 32 is moved to its stored position, abutting the conventional perforate end wall lining, it would result in an offset above the stored bulkhead which might be objectionable in view of the desirability of keeping the lading compartment walls flush and free from uneven surfaces. In order to provide this flush wall adjacent the end of the lengthened lading compartment, with the bulkhead of the invention, I provide novel means, best shown in Figs. 3 and 6. As best shown in Fig. 6, a plurality of vertically extending strips 80 may be rigidly affixed to the car end wall. A metal lining 82 may be affixed to the strips 80, in spaced relation with the car end wall, and ex-

tending over the lower portion of the end wall. A metal lining 84 may be provided above the lining 82 and in coplanar alignment therewith and extending over the upper portion of the end wall. The lining 84 may be spaced from the car end wall by a plurality of vertically extending strips 86 affixed to the lining 84 but not to the car end wall, a plurality of the strips 86 being in vertical alignment with a plurality of the strips 80 and swingably affixed thereto by means of links 88. Spaced apart vertically extending strips 90 may be affixed to the car end wall adjacent the upper portion of the lining 84, the strips 90 being arranged in pairs, one strip of each pair being on opposed sides of a strip 86 and being provided with a link 92 pivotally connected at one end thereof to the strip 90 and pivotally connected at its opposite end to the strip 86. The links 88 may comprise elongated flat plates or bars having apertures extending therethrough adjacent their opposed end portions and the links 92 may comprise similar plates or bars having an aperture in one end and a laterally extending stud bolt projecting outwardly from one of its plane sides. A keeper 94 may be affixed to the car end adjacent one side of one of the strips 86 and may have a slide bolt 96 associated therewith adapted to be manually slideable into and out of locking and unlocking engagement with the adjacent strip 86, whereby to hold the movable lining 84 against the car end wall or permit it to be swung away from the car end wall, respectively. The slide bolt 96 may be provided, intermediate its ends, with a laterally depending bar 98 adapted to be grasped by the operator, and the keeper 94 may be provided with a laterally extending horizontal flange 100 recessed at each end adapted to hold the bar 98 against sliding movement when the bar 98 is in vertical position; it being necessary to move the bar 98 up to a substantially horizontal position in order to slide the bolt 96 from one position to the other. The upper margin of the lining 82 may have cut-out portions 102, adjacent the links 88, whereby the links 88 may be swung from vertical to horizontal position as the lining 84 is swung outwardly from the car end wall. The keeper members 50, for anchoring the bulkhead bracing arms 48 to the end wall of the car may comprise pairs of angular members in spaced apart relationship affixed to the car end wall, intermediate the end wall and the lining 82. The angular members of the keeper 50 may be provided with aligned apertures and the bracing arm 48 may be secured to the keeper by means of a bolt 104 extending through the aperture 106 in the free end of the arm 48. The lining 82 may have cut-out portions 108 adjacent the keepers 50 in order to permit manipulation of the bolt 104. In order to move the lining 84 from the position shown in Figs. 2 and 6 to the position shown in Fig. 3, the slide bolt 96 would be moved to its right hand position (viewing Fig. 6) and the lining 84 may then be swung outwardly from the wall and rested upon the top portion of the stored bulkhead.

The side wall duct and bulkhead track means

The novel combination of the side wall duct and its associated track means is best shown in Figs. 4 and 5. The regular lading compartment side wall 110 may be outwardly offset adjacent the ice bunker and may be provided adjacent the upper portion of the offset wall with a metal lining 112 extending in a common plane

with the side wall 110. The lower portion of the outwardly offset wall portion may be provided with a metal lining 114 extending in a common plane with the side wall 110. The linings 112 and 114 may be mounted in spaced parallel relation with the offset wall portion upon vertical spacing strips 116, and may act as retaining walls for the ice adjacent the side wall of the bunker, providing the highly desirable side wall air ducts recommended by competent authorities. The track means for movably supporting the bulkhead may be disposed within the offset wall portion, intermediate the linings 112 and 114, and may comprise a horizontally disposed metal plate 118 secured, as by bolts, in flatwise abutting engagement with the offset wall portion and provided adjacent its ends with outwardly turned flanged ends. The track 54 may be affixed in parallel spaced relation with the lower portion of the plate 118 by means of a series of spaced apart vertically extending webs 120, the end portions of the track 54 having backing engagement with the flanged ends of the plate 118. In order to maintain the rollers 52 in operative engagement with the track 54, a substantially flat metal plate 122 may be removably mounted upon the plate 118 by means of set screws 124. The plate 118 may be provided with a plurality of outwardly extending bosses 126 rigidly affixed thereto and provided with threaded apertures adapted to receive the screws 124, the ends of the bosses having backing engagement with the plate 122. The plate 122 may be removed for the purpose of removing the bulkhead from the car. It will be noted that, although the track means is considerably lower in the car than the conventional track means adjacent the ceiling, it does not project into the lengthened lading compartment and provides a substantially flush surface with the side wall 110. It will also be noted that the track means and mounting therefor obstructs the important side wall duct to a negligible extent.

A latch member 128 may be secured to the top wall 10 adapted to hold the deflector 34 is raised operative position and may comprise a bar of angular configuration pivotally secured to the top wall 10 by means of mounting angles 130 and a pivot member 132, the latch member 128 being adapted to automatically fall into holding position with the deflector by gravity, as the deflector is raised to horizontal position. A locking member 134 may be pivotally and swingably secured to a vertical flange of one of the mounting angles 130 and may comprise an elongated rod having an eye at its upper end and two laterally projecting members 136 along one side of the rod; one of the members 136 being adapted to be inserted through a hole 129 in the latch member 128 to hold it in locked deflector supporting position, the other member 136 being adapted to be inserted through the same hole to hold the latch member 128 in a retracted, out-of-the-way position. The ends of the members 136 may be provided with apertures to receive a cotter or other securing means.

Means for raising the deflector 34, from vertical to horizontal position, may be provided, as best shown in Fig. 2, and may comprise a chain or light weight wire rope 138 secured at one end to one of the end portions of one of the posts 56 of the deflector, the chain or rope passing over a pulley 140 near the end wall and ceiling 20, and then passing over a pulley 142 affixed in a recessed portion 144 in the ceiling 18, above the extended bulkhead. One end of the chain

or rope 138 may depend from the pulley 142 and may be provided with a ring or other suitable grasping means 146. When the deflector is in vertical position the ring 146 may be closely adjacent the ceiling 18 and, after raising the deflector to horizontal position with the chain or rope 138, the ring 146 and the chain or rope adjacent thereto may be disposed adjacent the ceiling 18 and secured by a hook on the ceiling 18 or the upper portion of the side wall 110. It will be understood that the chain or rope 138, and its appurtenances, are not necessary to the operation of the bulkhead and deflector, as both the deflector and the bulkhead may be moved otherwise, from one position to another. If the chain or rope 138 is used, I prefer to locate it along the longitudinal center line of the car, where it will not be adversely affected by the dropping of ice through the hatches 22. There are usually two hatches in each end of the car, one on each side of the longitudinal center line, for which reason the locating of the chain or rope adjacent the center line of the car will place it between the hatches. The longer flange of the top frame member 58 may be notched out along its edge, adjacent the center line of the car, in order to permit the chain or rope to pass this flange when the deflector is in horizontal raised position. The use of the chain or rope 138, as a means of raising and lowering the deflector will add to the safety of operation, as the operator will be obliged to move farther away from the ventilator as it is moved to its horizontal position, and the danger of its accidentally falling upon him will be minimized.

The lower portion of the bulkhead 32 may be locked in both extended and stored positions by any of the conventional methods, such as vertical locking bolts on the bulkhead and movable into holding engagement with part of the floor structure, this means not being shown and forming no part of the present invention.

One or more of the bulkhead bracing arms 48 may be provided with a detent member 148 adapted to maintain the vertical deflector 34 against movement toward the car end, when the arm 48 is in secured horizontal position.

Reference to the "regular" lading compartment herein is intended to mean the lading compartment between extended bulkheads and the "lengthened" lading compartment refers to the lading compartment when the bulkheads are in stored position.

It is to be understood that the linings 46, 74, 82, 84, 112 and 114 may comprise imperforate or perforate material, wire mesh or expanded metal, without departing from the scope of the invention. The wooden linings 44 and 66 may be secured to their respective members in any of the conventional methods, as by clips, bolts or both. The metal linings may also be affixed to their respective mountings in conventional manner. Any of the parts which are indicated as being affixed to the car structure (and the specific fastening means not shown in the drawings) are intended to be secured by any of the conventional means, this means forming no part of the present invention.

Having thus described my invention, what I claim as new and desire to secure by Letters Patent is:

1. In a refrigerator car having an ice bunker at an end thereof separated from an adjacent compartment by a bulkhead including an upper section swingable to a stored position adjacent

the car top wall and a lower section movable to a stored position adjacent the car end wall; said upper section and said lower section having wall portions in substantial coplanar vertical alignment forming an end wall for said compartment.

2. In a refrigerator car having an ice bunker at an end thereof separated from an adjacent compartment by a bulkhead including an upper section swingable to a horizontal stored position adjacent the car top wall and a lower section movable to an upright position adjacent the car end wall; said upper section and said lower section being separated adjacent their lower and upper boundaries, respectively, adjacent the horizontal center line of the car.

3. In a refrigerator car having an ice bunker at an end thereof separated from an adjacent compartment by a bulkhead including an upper section hingedly and swingably secured to the car top wall and movable to a stored position parallel with the car top wall and a lower section supported by track means and movable to a vertical stored position adjacent the car end wall; said upper section and said lower section being separated adjacent their lower and upper boundaries, respectively, at a point removed from the top wall and the bottom wall of the car.

4. In a refrigerator car having an ice bunker at an end thereof separated from an adjacent compartment by a bulkhead including an upper section and a lower section separated adjacent their lower and upper boundaries, respectively, and movable to stored positions within the car; each section being provided with vertical spaced apart walls forming opposed walls of an air duct therebetween, the spaced apart walls of one section being in substantially coplanar alignment with the spaced apart walls of the other section and the air duct of each section being in substantially coplanar alignment with the air duct of the other section providing a substantially continuous vertical air duct throughout the aligned sections of the bulkhead.

5. In a refrigerator car having a convertible ice bunker in an end thereof separated from an adjacent compartment by a bulkhead including a swingably supported upper section and a rollably supported lower section, both sections being movable to stored positions within the car; said upper section and said lower section having plane boundaries forming the end wall of said compartment, said upper section and said lower section being divided coincident with their lower and upper boundaries, respectively, into complementary sections adapted to form said bulkhead.

6. A transverse bulkhead dividing the interior of a refrigerator car into separate compartments including an upper section swingable to a stored position parallel with and adjacent the car top wall and a lower section movable to an upright stored position adjacent the car end wall; the upper boundary of said lower section being coincident and parallel with the lower boundary of said upper section and being adapted for interlocking relationship with said lower boundary whereby to limit the movement of said upper section in one direction longitudinally of the car when said bulkhead is in operative position dividing the car interior into separate compartments.

7. In a refrigerator car having an ice bunker at an end thereof separated from an adjacent compartment by a bulkhead including an upper section and a lower section movable to stored positions within the car; said lower section being movable to a vertical position adjacent the lower

portion of the car end wall when stored; a wall section movably secured to said end wall above the stored lower section of the bulkhead adapted to be moved outwardly from said end wall to form a substantially coplanar continuation of the outer vertical wall of said stored lower section.

8. The combination of claim 7, wherein locking means is affixed to said end wall and adapted to selectively secure the movable wall section in retracted position adjacent said end wall and to permit said wall section to be moved to extended position away from said end wall.

9. In a refrigerator car having an ice bunker in an end thereof separated from an adjacent compartment by a bulkhead including an upper section and a lower section movable to stored positions within the car; said lower section having a vertically extending channeled portion open toward the car end wall, an elongated horizontally disposed bulkhead bracing arm movably secured adjacent one of its ends to said lower section and removably secured adjacent its opposed end to said end wall, said arm being selectively movable from its horizontal operative position to an inoperative vertical nested position within said channeled portion.

10. The combination of claim 9, wherein an end portion of said bracing arm is provided with a laterally disposed detent portion adapted to engage and limit the movement of said upper section in one direction longitudinally of the car when said arm is in horizontal operative position.

11. In a refrigerator car having an ice bunker in an end thereof separated from an adjacent compartment by a bulkhead including an upper section swingable to a stored position parallel with and adjacent the top wall of the car and a lower section movable to a vertical stored position adjacent the end wall of the car; said upper section and said lower section being separated coincident with their lower and upper boundaries, respectively, the lower margin of said upper section including detent means in overlapping engagement with said lower section adapted to limit the movement of said lower margin in a direction away from said end wall when the bulkhead is in extended operative position.

12. In a refrigerator car having an ice bunker in an end thereof separated from a lading compartment by a bulkhead including an upper section and a lower section movable to stored positions within the car; said bunker having a vertical air duct adjacent the car side wall and disposed intermediate the inner and outer surfaces of said side wall, said lower section being movable to an upright stored position adjacent the car end wall and being movably supported upon track means affixed to said side wall within the boundaries of said air duct, said lower section being provided with a member extending within said air duct and movably supported by said track means.

13. The combination of claim 12, wherein said track means is provided with a member adapted to maintain said lower section in cooperative movable engagement with said track means, said member being selectively removable from said track means to permit the removal of said lower section from cooperative engagement with said track means.

14. The combination of claim 12, wherein said track means is disposed within and intermediate the upper and lower portions of said vertical air duct, said track means including a

mounting member affixed to the outer wall of said duct and a track member secured to said mounting member in spaced relation therewith, and spaced apart connecting members affixed at one end to said mounting member and affixed at the opposed end to said track member, said track means being adapted to provide air communication between the upper and lower portions of the air duct, through said track means.

15. The combination of claim 12, wherein said track means is disposed within and intermediate the upper and lower portions of said vertical duct, said upper and lower portions of said duct being provided with wall portions substantially coplanar with the inner surface of the lading compartment side wall and forming retaining walls for the ice in the bunker, a horizontally disposed slot being provided coincident with said track member intermediate said upper and lower portions of said duct whereby to permit the movement of the lower section of the bulkhead longitudinally of the car.

16. In a refrigerator car having an ice bunker in an end thereof separated from an adjacent compartment by a bulkhead including an upper section and a lower section movable to stored positions within the car, said upper section being swingable to a retracted stored position parallel with and adjacent the car top wall; a pulley affixed to the car adjacent the free margin of the stored upper section, a second pulley affixed to the car top wall above the bulkhead, flexible means affixed to the lower portion of said upper section and extending progressively around said first named pulley and said second pulley, the free end of said flexible means depending from said second pulley within said compartment whereby a person in said compartment may raise and lower said upper section by manipulation of said flexible means.

17. In a refrigerator car having an ice bunker at an end thereof separated from an adjacent compartment by a bulkhead including an upper section and a lower section movable to stored positions within the car, said upper section being swingable to a stored position parallel with and adjacent the car top wall; a pivoted detent secured to the car adjacent a margin of the stored upper section selectively movable into and out of cooperative supporting engagement with said margin.

18. The combination of claim 17, wherein a locking member is secured to the car adjacent the pivoted detent and selectively movable into cooperative engagement with said detent adapted to maintain said detent in cooperative supporting engagement with said margin.

19. The combination of claim 17, wherein a locking member is secured to the car adjacent the pivoted detent and selectively movable into cooperative engagement with said detent whereby

to maintain said detent in cooperative supporting engagement with said margin, said locking member also being selectively movable into cooperative engagement with said detent adapted to maintain said detent in a retracted inoperative position.

20. In a refrigerator car having an ice bunker in an end thereof separated from an adjacent lading compartment by a bulkhead including an upper section and a lower section movable to stored positions within the car; said upper section having a vertically corrugated wall forming an ice retaining wall for said bunker and a spaced apart wall forming opposed walls of a vertical air duct therebetween, means forming an aperture in said spaced apart wall adapted to provide air communication between said lading compartment and said ice bunker, said corrugated wall being substantially imperforate opposite said aperture whereby to deflect air, passing from said lading compartment to said bunker through said aperture in a horizontal direction, in a downward direction into said vertical air duct.

21. The combination of claim 20, wherein the top wall of the car is provided with a hatch opening above the ice bunker and said upper section is swingable to a substantially horizontal position adjacent and underlying said hatch opening, the imperforate portion of the corrugated wall being in overlying relationship with said aperture when said upper section is in stored position adapted to deflect air and air-borne elements away from said aperture, the valleys of the corrugations being adapted to form horizontal air ducts to direct the deflected air and air-borne elements toward the end wall of the car.

22. The combination of claim 20, wherein said upper section is swingable to a substantially horizontal position adjacent and underlying a hatch opening in the car top wall above the ice bunker and when in this position the aperture has an upstanding peripheral flange adapted to prevent moisture and other elements from passing through said aperture after being deflected away from said aperture by the imperforate portion of the corrugated wall.

23. The combination of claim 20, wherein a hatch opening is provided in the car top wall above the ice bunker and said upper section of the bulkhead is swingable to a substantially horizontal position adjacent and underlying said hatch opening; the valleys of the corrugations in said corrugated wall forming horizontally disposed air ducts when the upper section is in said horizontal position adapted to direct the deflected air in a direction toward the end wall of the car, the ends of the corrugations adjacent said end wall being open and the opposed ends thereof being substantially dammed.
